ZODIAC CLOCK FACE

Lewis E. Zorzy, 20 Waterside Road,
Marblehead, Mass. 01945

Continuation-in-part of design application Ser. No.
18,420, July 25, 1969. This application Oct. 26,
1970, Ser. No. 25,655

Term of patent 14 years

Int. Cl. D10—07
U.S. Cl. D42—1

FIG. 1

FIG. 2

FIG. 1 is a top plan view of a clock face showing my new design; and

FIG. 2 is an edge elevational view.

This is a continuation-in-part of my application D. 18,420, filed July 25, 1969, and now abandoned.

I claim:

The ornamental design for a zodiac clock face, as shown and described.
